[57] CLAIM

The ornamental design for a computer carrying case, as shown and described.

DESCRIPTION

FIG. 1 is a top perspective view of a computer carrying case showing our new design, the broken lines which represent portions of a strap are shown for illustrative purposes only, forming no part of the claimed design; FIG. 2 is a rear elevational view thereof; FIG. 3 is a side elevational view thereof, the undisclosed side being substantially the same; FIG. 4 is a top plan view thereof; FIG. 5 is a bottom plan view thereof; FIG. 6 is a front elevational view thereof; FIG. 7 is a top perspective thereof, in an opened position; FIG. 8 is a front elevational view thereof; FIG. 9 is a right side elevational view thereof, the undisclosed left side being substantially the same; FIG. 10 is a rear elevational view thereof; and FIG. 11 is a top elevational view thereof. The broken lines in FIGS. 1, 3 and 7 represent conventional stitching.

The cross-lining in all views which represents conventional fabric is partially shown for ease of illustration only and is understood to cover the entire area as indicated.
